MULTIPLE POSITION SWITCH WITH MOVABLE CONTACT MOUNTED ON AN INSULATED SHAFT

Donald G. McArn and Percy E. Cook, Pittsburgh, Pa., assignors to Allis-Chalmers Manufacturing Company, Milwaukee, Wis., a corporation of Delaware

Application February 13, 1947, Serial No. 728,250

5 Claims. (Cl. 200—11)

1

This invention relates in general to improvements in electric switches, and more particularly to a selector switch of the type in which a contact shoe is movably mounted on a rotary shaft to cause selective bridging of a plurality of contact studs.

When a selector switch is built with a rotary shaft, it is generally advantageous to make the shaft of metallic material to obtain a shaft having a relatively large resistance to mechanical efforts for its size. However, the presence of an electrically conductive shaft increases the difficulty of preventing flashovers and surface discharges between switch elements operating at different potentials. It is therefore a general practice either to mount the movable contact on the shaft through insulating means, or to space the fixed contacts at a relatively great distance from the shaft. Both solutions render the switch relatively bulky and expensive.

By embedding the shaft in an actuating member of insulating material having a portion serving as a handle and a portion serving as a journal, the shaft may be made to support the movable contact without interposition of insulating material therebetween. The fixed contacts may then be disposed relatively close to the shaft without raising serious problems of insulation. The shaft may advantageously protrude into a cavity of the actuating member to serve as a fulcrum for the movable contact. A stop may also be provided on the actuating member to engage a fixed member when the shaft is in a predetermined position without thereby reducing the effectiveness of the shaft insulation, and to limit the movement of the movable contact when the actuating member is removed from the switch base.

It is therefore an object of the present invention to provide a multiple position switch in which the distance between a metallic shaft and adjacent fixed contacts may be reduced to a minimum.

Another object of the present invention is to provide a multiple position switch in which a movable contact is conductively mounted on a metallic shaft without thereby impairing the insulation between adjacent fixed contacts.

Objects and advantages other than those above set forth will be apparent from a consideration of the following description when read in connection with the accompanying drawing, in which:

Fig. 1 is a view in side elevation of a switch embodying the different features of the present invention.

2

Fig. 2 is a plan view of the embodiment illustrated in Fig. 1, and

Fig. 3 is a view of the embodiment illustrated in Fig. 1 partly in rear elevation and partly in vertical cross section taken along line III—III in Fig. 1.

Referring more particularly to the drawing by characters of reference, numeral 6 generally designates a switch base for a selector switch of a type adapted for effecting different connections between taps of a transformer winding. Base 6 is of generally slab-like shape and may be made of any suitable insulating material, such as molded synthetic resin. A bore 7 provided in base 6 has its axis substantially perpendicular to the body of the base. Bore 7 may be of uniform or non-uniform diameter, provided that its cross-section is circular at every point along its axis.

Base 6 is also provided, on both faces thereof, with a plurality of shoulders 8 molded integrally therewith and uniformly spaced on a circle centered on the axis of bore 7. Shoulders 8 may be all of uniform height, or may include a shoulder 9 which is made of greater height than the other shoulders and protrudes above the shoulder level for limiting the movement of the switch. Shoulders 8 serve for mounting a plurality of contact studs 11, which are thus likewise uniformly spaced on a circle centered on the axis of bore 7.

Studs 11 may be shaped in any suitable known manner to provide secure fastening of the studs in base 6. For example, the studs may be corrugated so as to interlock with the material of the base during the process of molding the base. Studs 11 are suitably shaped, at one extremity to provide a path for the movement of a movable contact shoe, and at the other extremity to provide for fastening current conductors thereto by soldering, crimping or otherwise.

The shaft 12 of the switch is made of suitable metallic material such as brass. Shaft 12 is of smaller diameter than bore 7 and is partially embedded in an actuating member generally designated 13. Member 13 may be made of any suitable insulating material such as molded synthetic resin. Secure fastening of shaft 12 in member 13 is obtained in any suitable known manner, as by making the shaft corrugated so as to interlock with the material of member 13 during molding thereof.

A portion of member 13 within which shaft 12 is embedded is of circular cross section to define a journal portion 14 fitting into bore 7 of base 6. The lower portion of shaft 12 protrud-

ing from journal 14 is provided with a circular groove or other indentation to receive a removable locking device such as a horseshoe shaped washer 15. A bushing 16 surrounding the protruding extremity of shaft 12 is locked between base 6 and washer 15 to prevent actuating member 13 from being withdrawn from bore 7. The upper extremity of shaft 12 protrudes into a cavity 17 provided in member 13 adjacent the level of the contact surfaces of studs 11.

The upper extremity of shaft 12 is shaped to define a pin 18 serving as a fulcrum for the movable contact shoe 19 of the switch. The shoe may be made of any suitable conductive material such as hard rolled sheet copper. The stud-engaging portion 21 of shoe 19 may be made V-shaped to impart a snap action to the switch. Shoe 19 may be further provided with a pair of parallel guide portions 22 adapted to slide along opposite vertical walls of cavity 17. Shoe 19 is formed with a hole of sufficient size to permit rocking movement of the shoe about pin 18, which extends through the hole.

Shoe 19 is biased toward studs 11 by suitable resilient means such as a helical spring 23 acting between shoe 19 and an extension of the upper wall of cavity 17. Spring 23 is prevented from moving out of operating position by a boss 24 provided on member 13 and by another boss formed on shoe 19 by indenting the shoe as at 25.

The lower wall of cavity 17 is provided with a projection 26 serving as a stop. The upper portion of member 13 is shaped to form a handle 27, which may be shaped as a pointer to indicate the position of the switch. The entire switch, or the switch with the exception of handle 27, may be immersed in a suitable insulating liquid (not shown).

It will be apparent that when studs 11 are connected to conductors at different potentials, shoe 19, the pair of studs in contact therewith and shaft 12 are brought to a predetermined common potential. Direct flashovers between the other studs and the shaft are effectively prevented by the portion of insulating member 13 surrounding the shaft. Shoulders 3 and member 13 also oppose to surface discharges between studs 11 and shaft 12 a creepage distance which may be made as large as desired without increasing the spacing between the studs and the shaft.

When handle 27 is turned to change the connections effected by the switch, shoe 19 rides on top of one or another stud 11. As a result of the V-shape of shoe portion 21, a torque is exerted on member 13 by spring 23 through shoe 19 and the stud 11 in contact therewith. After the apex of shoe portion 21 has passed over a stud, such torque causes shoe 19 to move further into another position bridging another pair of studs 11. Member 13 stops when equal torques are exerted thereon by spring 23 through shoe 19 and the two studs 11 in contact therewith. Movement of member 13 into the new position takes place with a snap action, so that no additional means are required to cause the member to stop in predetermined positions. Shoe 19 always stops in a position where spring 23 applies substantially equal pressures between shoe portion 21 and the two studs 11 in contact therewith.

During all movements of member 13, spring 23 biases downward the portion of shoe 19 extending into cavity 17, whereby the shoe is caused to remain securely anchored on pin 18.

When an attempt is made to rotate member

13 through a complete revolution in the one or the other direction, member 13 is stopped in one or another contact-making position by engagement of one of the lateral surfaces of stop 26 with shoulder 9. In this manner it is possible to prevent certain movements of the switch which might introduce disturbances in the operation of the circuits controlled thereby.

The action of spring 23 tends to cause journal portion 14 to be withdrawn from bore 7, but such action is prevented by washer 15 and bushing 16. By removing washer 15 member 13 may be removed from base 6. Shoe 19 is then no longer supported by studs 11, but its movement under the action of spring 23 is limited by application of the shoe against the upper surface of stop 26.

Member 13, shoe 19 and spring 23 may thus be handled as a unit, and may therefore also be assembled together prior to mounting on base 6. It will be understood however that regardless of whether or not member 13 is assembled on base 6, shoe 19 and spring 23 may easily be removed from cavity 17 by tilting the shoe so as to cause disengagement thereof from pin 18. Conversely, shoe 19 and spring 23 may be mounted in cavity 17 while member 13 is assembled on base 6. The steps involved in assembling and disassembling the switch may thus be effected in whatever sequence is found most convenient.

Although but one embodiment of the present invention has been illustrated and described, it will be understood by those skilled in the art that various changes and modifications may be made therein without departing from the spirit of the invention or from the scope of the appended claims.

It is claimed and desired to secure by Letters Patent:

1. A switch comprising a base of insulating material provided with a bore, a plurality of contact studs mounted on said base, said studs being uniformly spaced on a circle centered on the axis of said bore, a metallic shaft of diameter smaller than the diameter of said bore, an actuating member of insulating material comprising a journal portion in which said shaft is embedded, said journal portion being inserted in said bore and extending over the entire length of said bore for supporting said member for rotational movement about said axis, a contact shoe movably mounted on said shaft to bridge a selected pair of adjacent said studs, and resilient means acting between said actuating member and said shoe for biasing said shoe toward said studs.

2. A switch comprising a base of insulating material provided with a bore, a plurality of contact studs mounted on said base, said studs being uniformly spaced on a circle centered on the axis of said bore, a metallic shaft of diameter smaller than the diameter of said bore, an actuating member of insulating material comprising a journal portion in which said shaft is embedded, said journal portion being inserted in said bore for rotational movement of said member about said axis, said actuating member being provided with a cavity, one extremity of said shaft protruding into said cavity, a contact shoe rockably mounted on said extremity of said shaft to bridge a selected pair of adjacent said studs, and resilient means acting between a wall of said cavity and said shoe for biasing said shoe toward said studs.

3. A switch comprising a base of insulating material provided with a bore, a plurality of con-

tact studs mounted on said base, said studs being uniformly spaced on a circle centered on the axis of said bore, a metallic shaft of diameter smaller than the diameter of said bore, an actuating member of insulating material comprising a journal portion in which said shaft is embedded, said journal portion being inserted in said bore for rotational movement of said member about said axis, said actuating member being provided with a cavity, one extremity of said shaft protruding into said cavity, a contact shoe rockably mounted on said extremity of said shaft to bridge a selected pair of adjacent said studs, resilient means acting between a wall of said cavity and said shoe for biasing said shoe toward said studs, said resilient means tending to withdraw said journal portion from said bore, and means attached to the other extremity of said shaft to retain said journal portion in said bore against the action of said resilient means.

4. A switch comprising a base of insulating material provided with a bore and with a plurality of shoulders, said shoulders being uniformly spaced on a circle centered on the axis of said bore and comprising a protruding shoulder of greater height than the remaining said shoulders, a plurality of contact studs mounted on said shoulders, a metallic shaft of diameter smaller than the diameter of said bore, an actuating member of insulating material comprising a journal portion in which said shaft is embedded, said journal portion being inserted in said bore for rotational movement of said member about said axis, a contact shoe movably mounted on said shaft to bridge a selected pair of adjacent said studs, resilient means acting between said actuating member and said shoe for biasing said shoe toward said studs, and a stop member on said actuating member to stop the rotation of said actuating member upon engagement of said stop member with said protruding shoulder.

5. A switch comprising a base of insulating material provided with a bore and with a plurality of shoulders, said shoulders being uniformly spaced on a circle centered on the axis of said bore and comprising a protruding shoulder of greater height than the remaining said shoulders, a plurality of contact studs mounted on said shoulders, a metallic shaft of diameter smaller than the diameter of said bore, an actuating member of insulating material comprising a journal portion in which said shaft is embedded, said journal portion being inserted in said bore for rotational movement of said member about said axis, said actuating member being provided with a cavity, a contact shoe movably mounted on said shaft to bridge a selected pair of adjacent said studs, resilient means acting between said actuating member and said shoe for biasing said shoe toward said studs, and a stop member projecting from a wall of said cavity, said stop member having a surface against which said shoe is applied under the action of said resilient means when said actuating member is withdrawn from said bore to limit the movement of said shoe, said stop member having another surface which is applied against said protruding shoulder upon movement of said actuating member into a predetermined position to stop said actuating member.
